ABSTRACT

A connecting rod is divided into a plurality of sections along a transverse plane which are secured together by means of a plurality of bolts. A single liquid pressure jack is contained in one section to separate the sections.

FIG. 2

CONNECTING RODS OF INTERNAL COMBUSTION ENGINES

BACKGROUND OF THE INVENTION

This invention relates to a connecting rod of an internal combustion engine and more particularly a large size internal combustion engine for use in a ship or the like.

Generally, a connecting rod utilized in a large size internal combustion engine is composed of two sections bolted together so that one section connected with the piston can be withdrawn from the cylinder. These bolts are tightened or removed by means of a spanner or oil jacks which are provided for individual bolts. The spanner is not convenient for large size engines whereas provision of a plurality of oil jacks for individual bolts increases the cost of installation. Moreover, it is extremely difficult to mount the oil jacks on respective bolts because no scaffolding is available in the crank-case.

SUMMARY OF THE INVENTION

It is an object of this invention to provide an improved connecting rod of a split type wherein the split sections can be readily connected and disconnected in a narrow crank case of an internal combustion engine.

Another object of this invention is to provide an improved connecting rod of the split type wherein only one hydraulic jack is used for connecting and disconnecting the divided sections thereby decreasing the number of jacks and simplifying the pipings for supplying pressurized fluid to a plurality of jacks.

According to this invention there is provided a connecting rod for an internal combustion engine of the type wherein the connecting rod is divided into a plurality of sections along a transverse plane and the sections are connected together by means of a plurality of bolts, characterized in that a single hydraulic jack is contained in one section to separate said sections.

BRIEF DESCRIPTION OF THE DRAWINGS

In the accompanying drawings:

FIG. 1 is a front view of a piston, partly in section and a connecting rod embodying the invention;

FIG. 2 is a vertical sectional view showing an oil jack contained in one of the divided sections and

FIG. 3 is a front view of a modified embodiment of the invention.

DESCRIPTION OF THE PREFERRED EMBODIMENTS

A connecting rod 1 embodying the invention and illustrated in FIG. 1 is divided into two sections 2 and 3 along a plane perpendicular to the axis of the connecting rod 1 and located closer to the small end. These two sections, that is end section 2 and link section 3 are connected together by means of a plurality of bolts 4.

As shown in FIG. 2, a hydraulic jack 6 is embedded in the end surface 5 of the link section 3. The hydraulic jack 6 comprises a cylinder 8 secured to the link section 3 by means of a plurality of bolts 7, and a guide pin 10 extending through the bottom of the cylinder 8 and provided with an oil passage 9 for supplying oil to the compression chamber of an oil pressure cylinder to be described later. The link section 3 is formed with a lateral oil passage 11 which is communicated with oil passage 9. The outer end 12 of oil passage 11 is threaded

to receive a joint for supplying pressurized oil from a source of the pressurized oil not shown. A cylindrical piston 13 is slidably disposed in cylinder 8 so as to define the above described compression chamber 14. An O-ring 15 is interposed between the inner surface of the cylinder 8 and the outer surface of piston 13 to prevent the oil in the compression chamber 14 from leaking. A nut 19 is secured to the upper end portion of a cylindrical rod 17 extending through the central portion of the cylinder 8 to engage the bottom of a recess 18 formed in the upper end of piston 13. A spring seat 21 is formed on the lower end of rod 17 to support the lower end of a spring 20 for downwardly biasing the piston 13. The rod 17 is provided with a central bore 22 for passing cooling oil for a piston 23.

Although in this embodiment, the connecting rod 1 is divided into two sections along a transverse plane located near the small end, such a plane may be located near the big end of the connecting rod as shown in FIG. 3.

To assemble the end section 2 and the link section 3, a liner having a thickness t is interposed at the interface 5' between sections 2 and 3 and then bolts 4 are fully tightened to interconnect these sections. Then a pipe, not shown is connected to the threaded end 12 of the link section 3 to supply the pressurized oil into the compression chamber 14 so as to raise piston 13 as shown by arrow A, thereby increasing the gap at the interface to a value slightly larger than $t + \alpha$. Under these conditions, the liner having a thickness t is replaced by another liner having a thickness $t + \alpha$. Then the pressurized oil is discharged from the compression chamber causing piston 13 to restore. As a consequence, bolts 4 are elongated by a length α , the elongation α creating a strong clamping force for rigidly interconnecting sections 2 and 3.

Disconnection of sections 2 and 3 is performed in the opposite order. More particularly, after removing the liner having a thickness of $t + \alpha$, bolts 4 are loosened and removed thereby separating sections 2 and 3.

As above described, according to this invention, a connecting rod is divided into two sections along a transverse plane and a single hydraulic jack is provided in the central portion of either one of the divided sections at the transverse plane thereby enabling ready assembling and disassembling of the divided sections. Moreover, as only one hydraulic jack is used, it is not necessary to install a plurality of hydraulic jacks as in the conventional design. The only connection to be made in narrow crank casing is the connection of an oil pipe to the oil passage 11 so that it is possible to simplify the construction and save the labor.

Although the invention has been shown and described in terms of preferred embodiments thereof it should be understood that many changes and modifications will be obvious to one skilled in the art without departing from the true spirit and scope of the invention.

What is claimed is

1. In a connecting rod for an internal combustion engine of the type wherein said connecting rod is divided into a plurality of sections along a transverse plane and said sections are connected together by means of a plurality of bolts, the improvement which comprises a single hydraulic jack contained in one section to separate said sections.

2. The connecting rod according to claim 1 wherein said hydraulic jack comprises a cylinder disposed at the center of one section, a piston slidably received in said cylinder and means for supplying liquid under pressure to a pressure chamber between said cylinder and said piston.

3. The connecting rod according to claim 1 wherein said connecting rod is connected to the piston of said internal combustion engine and said cylinder and piston.

ton of said jack and said one section are provided with an opening for passing cooling fluid to said engine piston.

5 4. The connecting rod according to claim 1 wherein said connecting rod is divided into two sections along a transverse plane located close to one end of said connecting rod.
